UNITED STATES PATENT OFFICE

PAUL KUSHNIER, OF WARNEFORD, ONTARIO, CANADA

TRACK ALIGNING AND TIE TAMPING DEVICE

Application filed May 29, 1930, Serial No. 456,973. Renewed November 28, 1931.

This present invention relates to certain new and useful improvements in a track aligning and tie tamping device.

The primary object of the invention resides in the provision of a track aligning and tie tamping device which is highly efficient in use and may be readily handled by a single workman.

Another object of the invention resides in the provision of a track aligning and tie tamping device of the character stated which may be readily placed in position and adjusted for easy operation with the minimum expenditure of time, labour and expense.

15 A further object of the invention resides in the provision of a track aligning and tie tamping device of the character stated which is constructed so that it will perform the operation for which it is intended in the best manner possible without requiring more than one workman for duties which have heretofore required a number of workmen.

20 The invention has for a still further object the provision of a track aligning and tie tamping device of the character stated which will firmly hold the track while aligning the same or tamping the tie, without danger of either the track or the device moving out of set position.

25 The invention has for a still further object the provision of a track aligning and tie tamping device of the character stated which is composed of the minimum number of parts, of simple and inexpensive construction and arrangement and which may be readily assembled and adjusted with respect to one another.

30 The invention has for a still further object the provision of a track aligning and tie tamping device of the character stated which is of such construction that it may be readily manufactured at small cost and therefore may be produced for railway companies at a reasonable price.

35 The invention has for a still further ob-

ject the provision of a track aligning and tie tamping device of the character stated which will effect a considerable saving in the cost of labour and time and will stand strains to which it is subjected without injury to the 50 device and without ill effect on the track.

To the accomplishment of these and related objects as shall become apparent as the description proceeds, my invention resides in the construction, combination and arrangement of parts as shall be hereinafter more fully described, illustrated in the accompanying drawings, and pointed out in the claims hereunto appended.

55 The invention will be best understood and can be more clearly described when reference is had to the drawings, forming a part of this disclosure, wherein like characters indicate like parts throughout the several views.

60 In the drawings:—

65 Figure 1 is a plan view of the improved device with the parts assembled to adapt the device particularly for use as a track aligning device;

70 Figure 2 is a side elevation of the device, showing the same in use and operating against the far track rail, with the main portion of the device positioned between the track rails;

75 Figure 3 is a bottom plan view of the device;

80 Figure 4 is a detail fragmentary side elevation, showing clearly the upper portion of the body of the device;

85 Figure 5 is a longitudinal vertical section through the body of the device and the base thereof, showing clearly the parts operating within the body;

90 Figure 6 is a transverse horizontal section, taken substantially on the plane of line 6-6 of Figure 5, looking in the direction indicated by the arrows;

95 Figure 7 is a vertical longitudinal section, similar to Figure 5, showing a slightly modified form of the invention with the parts ar-

ranged for engagement under the near rail of the track, with a portion of the base extended beneath the rail;

Figure 8 is a transverse horizontal section, taken substantially on the plane of line 8-8 of Figure 7, looking in the direction indicated by the arrows;

Figure 9 is a side elevation of the device with the tie tamping mechanism mounted on the body, the view showing the manner of employing the device for tamping a tie;

Figure 10 is an elevation at right angles to Figure 9 and showing clearly the use of the device in the operation of tamping a tie; and

Figure 11 is a fragmentary detail plan of the device as shown in Figures 9 and 10, clearly illustrating the operating means for the side tamping mechanism of the device.

Referring more in detail to the drawings, it is to be noted that the device includes a base 16 which has prongs 17 extended downwardly at an angle from its lower face for engagement in the surface to prevent movement of the base 16 in one direction. Carried on the upper face of the base 16 is the upstanding arcuate hollow body 18 or post, which has a central elongated slot 19 in its concave side. The lever 20 extends through the slot 19 into the body 18 and has its rear end secured in the socket 21 provided therefor in the concave side of the slightly curved or arcuate rack bar 22 adapted to be raised within the body 18, along the inner face of the concave sides thereof. The rack bar 22 has downwardly directed rack teeth or ratchet teeth 23 on its convex face substantially the entire length thereof and with which teeth are engaged the long upper pawl 24 and the short lower pawl 25, both of which are pivoted at their enlarged lower ends on the pivot pins 26 and 27, projecting laterally from the forward extension 28 of the handle socket 29. It is to be understood that the pawls 24 and 25 have their lower ends bifurcated so as to straddle the extension 28 of the handle socket 29 and the pawl 24 is carried on the pivot pin 26 while the pawl 25 is carried on the pivot pin 27. The pivot pin 26 also serves as the pivot member for the handle socket 29. This handle socket 29 is mounted in the rear extension 30 of the body 18, at a point below the plane in which the socket 21 is positioned when the rack bar 22 is in its lowermost position within the body 18. The handle socket 29 works through the comparatively short longitudinal slot 31 in the rear extension of the body 18 and the main portion of the handle socket 29 is flared outwardly and provided with a socket opening 32 opening on the outer end of the handle socket 29 and tapering or steadily decreasing in diameter from its open outer end to its small rounded inner end 33. It will therefore be seen that an appropriate handle 34

may be readily secured by a tapered end in the handle socket 29 for use in operating the device. The handle socket 29 has a stop finger 35 extended therefrom at an angle and projecting into the slot 31 to engage the upper pawl 24 and thus thereby limit upward swinging movement of the handle socket 29 and the operating handle 34, carried therein. The upper pawl 24 may be readily withdrawn from the ratchet teeth 23 by means of the knob 36 projecting from the rear side of the pawl 24 for which the slot 31 is provided. A similar knob 37 projects from one side of the pawl 25 through the opening 38 in one side of the body or post 18, so that the lower pawl 25 may also be withdrawn from engagement with the ratchet teeth 23, when desired. By withdrawing both the upper pawl 24 and the lower pawl 25 from the ratchet teeth 23, the rack bar 22 may be permitted to return to its lowermost position within the body or post 18. The lower pawl 25 is normally retained in its operative engagement with the ratchet teeth 23 by the weight 39 carried on said pawl 25 and extending along one side of the rack bar 22. The lower pawl 25 may be held in its inoperative position, away from the rack bar 22, by means of the pivoted hook 40 which is mounted on the side of the handle socket 29, by the pivot member 41, preferably projecting laterally from the stop finger 35, said hook member 40 having an enlarged slotted working end 42 for engagement over the knob 37 when the pawl 25 is swung outwardly from the back bar 22 and the hook member 40 swung inwardly on its pivot 41. When the hook member 40 is in its normal inoperative position, it extends outwardly and rests on the supporting lug 42 provided therefor and projecting from the side of the handle socket 29, outwardly of the pivot member 41. The remaining end 43 of the hook member 40 is directed downwardly at an angle to the main portion thereof to limit swinging movement of the hook member 40 on its pivot 41.

For the purpose of transporting the device, a pair of loop handles 44 may be provided on the sides of the body 18 or a single handle 45 on the rear convex side thereof, as desired. When the pair of handles 44 are employed, the device may be conveniently carried by two workmen, one on either side thereof. When the single handle 45 is employed, the device may be more conveniently carried by one workman.

The lever 20 is pivotally mounted near its forward lower end on the fulcrum member 46 which is extended transversely through the reduced bifurcated end 47 of the forward base plate extension 48. The lever 20 terminates in the flat track shifting member 49 which is of substantially diamond shape in plan and adapted for engagement transversely beneath

one of the rails of the track for shifting and thereby aligning the track as the device is operated, after being properly set in position between the track rails.

5 By referring to Figures 7 and 8, it will be seen that the slots 19 of the body 18 may be extended to the bottom of the body and thereby provide for accommodating the laterally extended neck 50 at the bottom of the rack bar 22 and on which neck 50 is carried the rail lifting member 51 in the form of a plate normally resting on the base plate 16 and adapted to be engaged beneath the track rail adjacent which the body 18 is positioned. In 10 this form a portion of the base plate 16 also extends beneath the track rail and may be formed separate from the body 18 and the latter mounted on the base plate 16 by bolts 52 or the like extended upwardly through 15 said base plate 16 and through lateral flanges 53 extended from the bottom of the body 18. Otherwise, the construction and arrangement of the parts of the base plate 16 and body 18 are the same as disclosed in the Figures 1 to 20 5 inclusive. In this form shown in Figures 7 and 8, however, the base plate 16 is not extended and bifurcated as in the first form and the lever 20 is not required.

For both forms shown in Figures 1 to 5 inclusive and in Figures 7-8, the slot 19 may either have the upper end thereof closed or may have its upper end opening on the upper end of the body 18 and furthermore, the base plate 16 may be formed separate from or integral with the body 18, as preferred. In 25 both of these forms of the device, the operating handle and handle sockets 29 are manipulated in the same manner to force upwardly the rack bar 22 and thus cause the parts controlled thereby to function in raising or shifting the track rail engaged thereby.

For tamping a tie, special mechanism is supported on the body 18 and this mechanism includes a bracket plate 54, mounted on one 30 side of the body 18, near the upper end thereof, as shown clearly in Figures 9, 10 and 11. This bracket plate 54 has forwardly extended arm 54a at its forward upper corner and on which a bearing 55 is carried to support the upper end of the vertical rod 56 adapted to reciprocate therethrough. A pair 35 of bearings 57 are also carried on the bracket plate 54, adjacent the lower edge thereof and through which is rotatably mounted the horizontal shaft 58. This shaft 58 carries a bevelled gear 59 on one end with which is engaged the driving gears 60 carried on one end of the transverse driving shaft 61. This transverse driving shaft 61 rotates through 40 the rear lower corner of the bearing plate 54 and through a second bearing plate 62 secured on the other side of the body 18. The driving shaft 61 has one end extended as a crank 63 with an operating knob or handle 64 mounted thereon, whereby the driving shaft

61 may be readily rotated by hand. The shaft 58 has a wheel 65 mounted thereon, concentrically with an eccentric pin 66 projecting from its outer face and having mounted thereon the link 67, which is also mounted 70 at its other end on the pin 68 projecting radially from the collar 69 which is rigid on the lower portion of the vertical rod 56. Thus, as the crank 64 is operated, the shaft 58 is rotated and, through the medium of 75 the wheel 65, the eccentric pin 66, the link 67, the pin 68 and the rigid collar 69 on the vertical rod 56, the latter is reciprocated vertically in the bearing 55 and in the lower guide bearing 70 carried on the forward end 80 of the supporting arm 71 projecting from the side of the body 18, below the bearing plate 54. On the lower end of the rod 56, a sleeve 72 is carried, through which is adjustably secured the transverse horizontal 85 rod 73, firmly secured in its adjusted position by the set screw 74 in the sleeve 72 or by other appropriate means. A sleeve 75 is adjustable longitudinally on one end of the rod 73 and retained in adjusted position 90 thereon by a set screw 76 or other appropriate means. An arm 77 depends from the sleeve 75 and has adjustable thereon the collar 78 held in adjusted position by a set screw 79 or other means. Diverging and 95 downwardly inclined arms 80 project from diametrically opposite points of the collar 78 and are rigid therewith. Pivoted to the outer lower ends of the arms 80 are the tamping arms 81 which depend and converge 100 slightly toward one another for operation at opposite sides of the ties to be tamped. The tamping arms 81 have enlarged or widened lower working ends 82 and they are resiliently retained in their innermost positions 105 by the respective springs 83 connecting the tamping arms 81 with the arms 80 by which they are suspended. During the operating of the tamping mechanism, the rail is retained in elevated position, as by the rail 110 supporting plate 51 and the crank handle 64 is operated to cause raising and lowering of the rod 56 to elevate the transverse horizontal rod 73 and thus raise the tamping arms 81 repeatedly, permitting them to automatically lower and tamp the material at the opposite sides of the ties, after each raising of the rod 56.

As the construction of the device has thus been described in detail brief reference is now 115 had to its use and modus operandi: When this device is to be employed either for aligning the track or tamping a tie, the complete device is properly positioned by the side of the track or between the rails and also between and longitudinally of a pair of the ties supporting the rails. When the device is positioned between the rails, the track aligning member 49 is properly positioned beneath the rail on which it is to operate with the pawls 120 125 130

24 and 25 properly engaged with the ratchet teeth of the rack bar 22, it is then only necessary to oscillate the actuating handle engaged in the handle socket 29 and thereby cause the pawls 24 and 25 to alternately move on the ratchet teeth of the rack bar 22 and raise the latter in the body 18. This causes a tilting of the lever 20 and the member 49, thus pressing upwardly on the rail and causing the same to slide on the tilted member 49 until the track is properly aligned. During this operation, the prongs 17 will serve to firmly hold the body 18 and base plate 16 in set position. When it is desired to permit return of the lever 20 and the member 49 to normal position, the pawls 24 and 25 may be readily disengaged from the ratchet teeth of the rack bar 22 and maintained in withdrawn position until the rack bar 22 is completely returned to its lowermost or normal position, together with the lever 20 and the member 49. When the device is employed to raise one of the track rails by means of the member 51, this member 51, together with the projecting portion of the base plate 16 should be properly positioned beneath the rail and the actuating handle carried in the handle sockets 29 oscillated to raise the rack bar 22 and thus elevate the member 51 with the rack bar 52 until the rail is raised to the desired position. Without withdrawing the device, the rail may be maintained in this raised or elevated position and the tamping mechanism then operated by means of the crank 64 to cause a thorough tamping of the material at both sides of the tie over which the sleeve 75 is positioned. While all of the parts of the tamping mechanism are supported on the body 18, they do not in any way interfere with the efficient operation of the track aligning or rail elevating mechanism also carried by the body 18. However, the body 18 serves as the supporting and carrying means for all of the mechanism of the device.

From the foregoing description taken in connection with the accompanying drawings, it will be manifest that a track aligning and tie tamping device is provided that will fulfill all the necessary requirements of such a device but as many changes could be made in the above description and many apparently widely different embodiments of my invention may be constructed within the scope of the appended claims without departing from the spirit or scope thereof, it is intended that all matters contained in the said accompanying specification and drawings, shall be interpreted as illustrative and not in a limited sense.

Having thus described my invention, what I claim as new and desire to secure by Letters Patent is:—

1. A track aligning and tie tamping device including a base; a body carried on said base; a rack bar operable in said body; means

controlled by said rack bar; and means operating through said body for elevating said rack bar within said body.

2. A track aligning and tie tamping device including a base; an arcuate body carried on said base; a rack bar operable in said body; means controlled by said rack bar; co-operating pawls for raising said rack bar in said body; and a handle carrying member working through said body and supporting said pawls.

3. A track aligning and tie tamping device including a base; a body carried on said base; a rack bar operable in said base; a rail engaging member controlled by said rack bar; an actuating handle carrying socket working in said body; pawls carried on said handle carrying socket for operating on said rack bar to raise the latter in said body; and tie tamping mechanism carried by said body.

4. A track aligning and tie tamping device including a base; a body mounted on said base; a rack bar operable within said base; track rail engaging means connected with said rack bar and operable with the same; handle carrying means working through said body; pawls carried on said handle supporting means and operatively engaged with said rack bar to raise the latter in said body; and tie tamping mechanism carried by and operable on said body.

5. A track aligning and tie tamping device including a base; an arcuate body carried on said base; a rack bar operable in said body; handle carrying means working in said body; pawls carried by said handle carrying means for raising said rack bar in said body; a track rail engaging member operable with said rack bar; and a tie tamping mechanism operable on said body and supported by the latter.

6. A track aligning and tie tamping device including a base; a slotted body carried on said base; a rack bar operable in said body; handle supporting means operable in said body; pawls carried by said handle carrying means and engaged with said rack bar to operate the latter in said body; a track rail engaging member connected with said rack bar and operating through the slot of said body; and tie tamping mechanism supported on said body and operable thereon.

7. A track aligning and tie tamping device including a base; a body carried on said base; handle supporting means working through one side of said body; a rack bar within said body and operable therein; means extended from said rack bar and working through the opposite side of said body for operation on a track rail; rack bar operating members carried by said handle supporting means; tie tamping mechanism carried by said body and operable thereon; and actuating means for said tie tamping mechanism.

8. A track aligning and tie tamping device including a base; a body carried on said base; a rack bar operable in said body; track rail engaging means operable by said rack bar and working through said body; handle supporting means working through said body; rack bar operating means carried by said handle supporting means; a pair of tie tamping members; a supporting means for said tie tamping members; a lifting rod for said tie tamping supporting means; means for mounting said lifting rod on said body; means carried on said body for operating said lifting rod; and actuating means for the said last mentioned means.

In testimony whereof I hereunto affix my signature.
